UNITED STATES PATENT OFFICE.

FRANK S. BARKS, OF ST. LOUIS, MISSOURI, ASSIGNOR TO LINCOLN STEEL AND FORGE COMPANY, OF ST. LOUIS, MISSOURI, A CORPORATION OF MISSOURI.

TRUCK-FRAME FOR MINE-CARS.

1,389,928.

Specification of Letters Patent.

Patented Sept. 6, 1921.

Application filed February 4, 1921. Serial No. 442,402.

To all whom it may concern:

Be it known that I, FRANK S. BARKS, a citizen of the United States, residing at St. Louis, Missouri, have invented a certain new

5 and useful Improvement in Truck-Frames for Mine-Cars, of which the following is a full, clear, and exact description, such as will enable others skilled in the art to which it appertains to make and use the same, reference being had to the accompanying drawings, forming part of this specification.

10 My invention relates generally to mine cars and more particularly to the truck frame and journal boxes therefor, the principal objects of my invention being to generally improve upon and simplify the construction of mine car truck frames and journal boxes and to provide a relatively simple, strong and durable truck frame that can be 15 easily and cheaply manufactured, readily applied to mine cars and which will serve as a firm and substantial support for the journal boxes in which the wheel carrying axles are journaled.

20 25 Further objects of my invention are, to provide a mine car truck frame with pockets that are adapted to receive and retain the journal boxes and the latter being constructed so that they are self-aligning, thereby 30 eliminating the time and labor ordinarily involved in setting the journal boxes in true positions.

35 A still further object of my invention is to provide an improved form of journal box for mine car truck frames and to construct the same so that grease or liquid lubricant can be readily delivered into the chamber within the box.

40 45 With the foregoing and other objects in view, my invention consists in certain novel features of construction and arrangement of parts hereinafter more fully described and claimed and illustrated in the accompanying drawings, in which—

45 Figure 1 is a top plan view of a mine car truck frame of my improved construction.

Fig. 2 is a section taken approximately on the line 2—2 of Fig. 1.

50 Fig. 3 is an end view of the truck equipped with a frame of my improved construction.

Fig. 4 is an enlarged cross-section taken approximately on the line 4—4 of Fig. 1.

55 Fig. 5 is a detail section taken approximately on the line 5—5 of Fig. 4.

Fig. 6 is a horizontal section taken approximately on the line 6—6 of Fig. 5.

Fig. 7 is a partial plan view of a modified form.

Fig. 8 is an end elevational view partly in section of the modified form shown in Fig. 7.

Fig. 9 is a detail view, inside elevation, of the modified form shown in Figs. 7 and 8.

Referring by numerals to the accompanying drawings which illustrate a practical embodiment of my invention, 10, 10 designate the side members of my improved truck frame, said members being preferably constructed from commercially rolled channels disposed with their flanges projecting downwardly and said beams near their ends being bent downwardly to form substantially U-shaped portions 11 that serve as bearings or pockets for the journal boxes that are associated with the truck. The webs of these 15 side members 10 are provided at suitable points with perforations 12 that are adapted to receive bolts or like fastening devices that secure the truck frame to the underside of the car body and the transversely disposed 20 frame members 13 that are preferably formed of commercially rolled channels have their end portions positioned within the upper portions of the spaces within the bearings or pockets 11 and the depending flanges 25 of said transverse frame members are secured to the upper portions of the U-shaped bearings or pockets 11 of the side members 10 in any suitable manner, preferably by means of rivets 14. The end portions of the 30 webs of the transverse members 13 are bent or pressed upwardly as designated by 15, such construction being employed in order to accommodate bearing lugs that are formed integral with the tops of the journal 35 boxes.

The bodies 16 of these journal boxes are substantially cylindrical in form and the annular surface 17 of the wall inclosing the main chamber in each box is smooth in order to form a bearing surface for antifriction members such as rollers 18 which surround the journal of the wheel carrying axle 19 and these antifriction members 18 are retained within the journal box in any suitable manner.

100 105 The body of each journal box is provided with an enlargement 20 so that when the

journal box is properly positioned in the bearing or pocket 11, it may rock slightly in vertical and horizontal directions, thereby making it self-aligning with respect to its 5 companion journal box and the axle journaled therein.

Formed integral with the top of the body portion 16 of each journal box is an upwardly projecting lug 21 having a rounded 10 upper surface which, when the box is properly positioned bears against the under-surface of the raised portion 15 of the transverse frame member 13. Formed integral with that portion of the body 16 of each 15 journal box that projects beyond the U-shaped bearing 11 are laterally projecting ears 22 with the inner faces of which are formed vertically disposed lugs 23, the faces of which are convex and when the boxes are 20 properly positioned in the bearings 11 these curved faces bear directly against the outer faces of the outer flanges of those portions of the beams 10 that are bent downwardly to form the bearings 11. (See Figs. 4 and 25 6.) These lugs 23 perform the functions of stops to limit the inward movement of the journal boxes with respect to the truck frame and likewise they serve as rocking bearings during any vertical swinging movement of the boxes while the same are aligning 30 themselves with each other and with the carried axles.

Formed through one of the laterally projecting ears 22 is a port or passageway 24, 35 the outer end of which is closed by a removable member 25, such as a screw plug, and this construction permits grease or liquid lubricant to be readily delivered into the chamber within the journal box and which 40 is occupied by the anti-friction members 18.

A mine car truck frame of my improved construction is comparatively simple, may be easily and cheaply produced inasmuch as its principal parts may be constructed from 45 ordinary commercial shapes, is very strong and durable, and the journal bearings associated with the truck are located in the frame so that they may rock freely in all directions, thereby permitting them to align 50 themselves with each other and with the journaled axles.

In Figs. 7 to 9, inclusive, I have shown a modified form of frame in which it will be noted that the side frame 10^a is in the form 55 of a flat plate or bar having U-shaped depressions 10^b formed near its ends for receiving the ends of the cross-channels 13, as hereinbefore described.

In all forms of my invention, it will be 60 noted that the side frame members 10—10^a and the cross-members 13 are on the same horizontal plane so that the floor or deck timbers arranged thereon must be notched out above the upwardly bent portions 15 at 65 the ends of the cross members. By having

the central portions of the cross-members 13 depressed, it is possible to mount the journal boxes in the raised portions at the ends thereof without increasing the floor height of the car over that which is usual where 70 wheels with plain bearings are employed.

I claim as my invention:

1. A mine car truck frame comprising a pair of side members, portions adjacent to the ends thereof being substantially U-shape, 75 transverse members having their end portions seated in the U-shaped portions of the side members, and, journal boxes positioned within the U-shaped portions of said side members and beneath the end portions of 80 said transverse members.

2. A mine car truck frame comprising a pair of side members, portions adjacent to the ends thereof being substantially U-shape, 85 transverse members having their end portions seated in the U-shaped portions of the side members, journal boxes positioned within the U-shaped portions of said side members and beneath the end portions of 90 said transverse members, and frame engaging 95 members formed on said journal boxes.

3. A mine car truck frame comprising a pair of side members, portions adjacent to the ends thereof being substantially U-shape, 95 transverse members having their end portions seated in the U-shaped portions of the side members, and, journal boxes arranged for universal rocking movement within the U-shaped portions of said side members and beneath the end portions of 100 said transverse members.

4. A mine car truck frame comprising a pair of side members, portions adjacent to the ends of which are bent to form substantially U-shaped bearings, transverse frame 105 members having their ends positioned in the upper portions of said U-shaped bearings, and journal boxes loosely arranged within said U-shaped bearings.

5. A mine car truck frame comprising a 110 pair of side members, portions adjacent to the ends of which are bent to form substantially U-shaped bearings, transverse frame members having their ends positioned in the upper portions of said U-shaped bearings, and journal boxes mounted for universal 115 rocking movement within said U-shaped bearings and having parts that engage with said U-shaped bearings and with the end portions of the transverse members.

6. A mine car truck frame comprising a pair of side members, portions adjacent to the ends of which are bent to form substantially U-shaped bearings, transverse frame 125 members having their ends positioned in the upper portions of said U-shaped bearings, journal boxes mounted for universal rocking movement within said U-shaped bearings and having parts that engage with said U-shaped bearings and with the end portions 130

- of the transverse members, and lugs projecting laterally from the outer portions of the journal boxes and adapted to bear against the outer faces of the U-shaped bearings.
- 5 7. The combination with a mine car truck frame having side members in which are formed U-shaped bearings, of journal boxes mounted for rocking movement in said U-shaped bearings, and lugs projecting laterally from the outer portions of said journal boxes, which lugs are adapted to bear against the outer faces of said U-shaped bearings.
- 10 8. The combination with a mine car truck frame having side members in which are formed U-shaped bearings, of journal boxes mounted for rocking movement in said U-shaped bearings, lugs projecting laterally from the outer portions of said journal boxes, which lugs are adapted to bear against the outer faces of said U-shaped bearings, and wheel carrying axles journaled in said journal boxes.
- 15 9. The combination with a mine car truck frame having side members in which are formed U-shaped bearings, of journal boxes mounted for rocking movement in said U-shaped bearings, lugs projecting laterally from the outer portions of said journal boxes, which lugs are adapted to bear against the outer faces of said U-shaped bearings, and there being a lubricant opening formed in one of the lugs on each journal box.
- 20 10. A mine car truck frame comprising frame members having depressed central portions for supporting the flooring of the car.
- 25 11. A mine car truck frame member having raised or elevated end portions in which journal boxes may be secured.
- 30 12. A mine car frame consisting of connected members lying in the same horizontal plane and constituting a floor support, certain of said members having raised portions in which journal boxes may be secured.
- 35 13. A mine car truck frame comprising side members depressed at their ends to accommodate journal boxes, and cross mem-
- bers raised at their ends to accommodate said journal boxes, the floor line of said frame members being in a horizontal plane which is located between the top and bottom surfaces of the journal boxes.
- 40 14. In a mine car truck, a journal box, and a frame member having a depressed portion to accommodate said journal box and having a floor supporting surface below the top surface of said journal box.
- 45 15. In a mine car truck, a journal box, and a frame member having a raised portion to accommodate said journal box and having a floor supporting surface below the top surface of said journal box.
- 50 16. In a mine car truck frame, a transverse member consisting of a structural channel, the web of which is disposed horizontally and is provided with upwardly extending depressions at its opposite ends, each adapted to receive a journal box.
- 55 17. In a mine car truck frame, a side member consisting of a structural channel which is bent downwardly and then upwardly near each end to form a U-shaped journal box containing member.
- 60 18. In a mine car, longitudinal and transverse members secured to each other and at their securing points being respectively recessed in opposite directions to receive a journal box between them.
- 65 19. In a mine car truck frame, parallel side members consisting of structural channels, the webs of which are disposed horizontally with their flanges facing downwardly and which channels are bent near their ends to form U-shaped journal box containing recesses, and transverse members consisting of structural channels, the webs of which are disposed horizontally with their flanges facing downwardly and which channels fit near their ends between the sides of said recesses, the flanges of said transverse members being secured to the bent webs of said side members.

In testimony whereof I hereunto affix my signature this 28th day of December, 1920.

FRANK S. BARKS.
